UNITED STATES PATENT OFFICE.

CHARLES A. PSILANDER, OF EASTON, PENNSYLVANIA, ASSIGNOR TO WILLIAM WHARTON, JR. & CO., OF EASTON, PENNSYLVANIA, A CORPORATION OF PENNSYLVANIA.

HARD-CENTER CROSSING-FROG.

1,327,842.

Specification of Letters Patent.

Patented Jan. 13, 1920.

Application filed September 3, 1919. Serial No. 321,405.

To all whom it may concern:

Be it known that I, CHARLES A. PSILANDER, a citizen of the United States, residing at Easton, in the county of Northampton and State of Pennsylvania, have invented certain new and useful Improvements in Hard-Center Crossing-Frogs, of which the following is a specification.

Prior to my invention centers having a driving fit in a frog or crossing body have been proposed, but they have not been adopted because they could not be removed for repair or replacement purposes without tearing up the track.

My invention provides a renewable and reversible hardened frog and crossing center having a machine fit and self-contained means whereby it may be readily removed for repair or adjustment purposes. The improved center obviates the use of filling or grouting and requires no auxiliary fastenings.

The nature, characteristic features, and scope of the invention will more readily be understood from the following description taken in connection with the annexed drawings, forming a part hereof, wherein—

Figure 1 is a plan view of my improvements applied to a frog.

Fig. 2 is a similar view of my improvements applied to a crossing.

Fig. 3 is a section on line 3—3 of Fig. 1.

Fig. 4 is a section on line 4—4 of Fig. 2.

The usual track body 5 is provided with a circular depression or cored portion 6, which receives with a driving fit a correspondingly shaped plug or hardened center 7, the contacting surfaces of the recess and center being machined and ground for this purpose. The chamber 8 formed by the depending marginal wall or skirt of the plug communicates with a channel 9 in the track body 5. The channel extends to the top of the track body and is closed by a countersunk screw-cap 10, which can be readily re-

moved, as by means of a screw-driver, in fitting or removing the plug. In order to remove the plug, fluid pressure, which, for example may be supplied by a portable pump, is admitted to the chamber 8, via 50 the channel 9. The annular groove or space 11, intermediate the plug and track body, is useful, when present, as a leakage space for pressure fluid and increases the effective area of the plug acted upon by the fluid. 55

In the modification, Figs. 2 and 4, the plug or center 12 has a driving or machine fit in the crossing body 13. The plug has a bottom chamber or subway 14 to which fluid pressure may be admitted from a channel 15 60 extending to the top of the plug. The closure for the channel may be a nipple 16 with a countersunk cap 17.

Having described my invention, I claim:

1. In a track structure, a center having a 65 driving fit, and means for ejecting it with fluid pressure.

2. In a track structure, a center having a fluid-tight fit, a chamber formed partly by the center, and means whereby it may be 70 supplied with fluid pressure to eject the center.

3. In a track structure, a center having a fluid-tight fit, a chamber formed partly by the center, means whereby it may be supplied with fluid pressure to eject the center, and means for increasing the effective area 75 to be acted upon by the fluid pressure.

4. A track structure having a fluid pressure chamber of which an element is a center having a driving fit, and a normally closed fluid supply channel communicating with said chamber. 80

5. A track structure having a fluid pressure chamber of which an element is a center having a driving fit, a fluid supply channel communicating with said chamber, and a countersunk stopper for said channel. 85

In testimony whereof I affix my signature.

CHARLES A. PSILANDER.
